DOUBLE GRID ELECTRON TUBE AND CIRCUIT

Heinz Lux, Berlin, Germany, assignor to Telefunken Gesellschaft für Drahtlose Telegraphie m. b. H., Berlin, Germany, a corporation of Germany

Original application November 16, 1932, Serial No. 642,845. Divided and this application May 27, 1936, Serial No. 82,001. In Germany November 17, 1931.

6 Claims. (Cl. 250—27.5)

This application is a division of my application, Serial No. 642,845, filed Nov. 16, 1932, for "Double grid electron tube and circuit" which has now matured into Patent No. 2,067,156.

In the methods discovered by Barkhausen and Kurz for producing oscillations by means of braking fields, the electrons, as is known, perform pendulum movements around the highly positive grid of a 3 electrode tube in which the anode has the potential of the cathode or a weak negative voltage. The electrons emitted by the filament participate, if they are not affected by particular measures, only to the smallest extent in the pendulum movements, whereas the major amount of electrons move in a straight line towards the grid where they produce heat and thereby limit the loading capacity of the tube. The proportion between the grid losses and the oscillating power is about 100:1. An explanation for this phenomenon can be found when considering the electric field between grid and filament, the shape of which is shown in Figure 1. All of the electrons which enter the straight or only slightly curved fields will move to the grid in a straight line. Only at such places where the lines of force have a considerable curvature, the electrons do not follow the latter but maintain, due to their mass inertia, the straight path and then carry out the desired pendulum movements.

The object of the present invention is to provide such field distribution so as to avoid as much as possible straight lines of force extending between the grid and the filament. As a result a larger portion of the emitted electrons is caused to carry out pendulum movements and the supply of non-oscillating electrons to the grid is reduced. This causes a decrease of the grid load and also an increase of the grid potential which in turn enables a decrease of the wave length.

In the drawing Fig. 1 illustrates diagrammatically the electric field between the several electrodes of a three-electrode tube. Fig. 2 illustrates diagrammatically a four-electrode tube according to the present invention, and the electric field between the electrodes thereof. Fig. 3 illustrates a practical embodiment of the tube shown in Fig. 2 in connection with either a transmitting circuit or a receiving circuit. Fig. 4 is a detail view showing schematically the relation of one form of a pair of grids according to the invention, Fig. 5 is a transverse sectional view showing the relation of another form of a pair of grids according to the invention, and Fig. 6 is a view similar to Fig. 5 and showing a modification

thereof. In order to obtain the desired field distribution it is suggested to provide for instance a second grid between the filament and the positive grid electrode. In Figure 2 the filament is shown as 1, the positive grid is shown as at 2 and the anode of a 3-electrode tube is designated at 3. The wires of the second grid 4 must be arranged in such manner so as to be on a straight line through grid 2 perpendicular with respect to anode 3 and filament 1. When a spiral shaped grid is provided, two helices are obtained (Fig. 4) which are of equal pitch but of a different diameter and the wires as such determine an orthogonal screw surface. Where a rod shaped grid is used, as shown in Fig. 5 the single rods must be 10 in the same radial plane. When these requirements are fulfilled the field distribution follows the course shown in dotted lines in Figure 2. A deviation from this required arrangement would however be of detrimental effect to a tube, as compared with a tube having only one grid. The grid 4 may either be connected to the cathode, or may have a negative potential applied to it. It will charge negatively as a free grid and thus also fulfill its purpose.

In order to prevent the electrons from directly impinging upon the grid, a screen may be provided composed of dielectric materials such as mica, glass or quartz whereby the shape must be in accordance with the same principle as referred to above in connection with a metallic screen grid of the type shown in Figs. 4 and 5. In Fig. 6 there is shown the modification just described in connection with rod shaped grids. The screen of dielectric material is indicated by 30 35 and the positive grid of metal by 20".

The manner in which my improved double grid tube may be used in a transmitter is illustrated in Figure 3. Modulating audio frequency potentials from microphone 5 and audio frequency amplifier 6 are applied to the anode 8 through the transformer 10. The secondary of transformer 10 is connected in series with the lead 12 maintaining the anode at a highly or slightly negative potential with respect to the 40 filament 14 which is energized to an electron emitting condition by the action of heater battery 16 and filament voltage adjusting resistor 18.

The grid 20 through which the electrons make their pendulum-like movements is maintained at a highly positive potential by the action of source 21 applying a positive voltage to it through lead 22. Chokes 24 are provided to prevent undesired flow of high frequency current in the polarizing leads and sources.

The added grid 26 according to my present invention is maintained either at filament potential or at a slightly negative potential by the suitable tapping of lead 28 on to negative biasing source 30 5 or directly on to the filament lead 32. Oscillatory energy will then be developed in the Lecher wire system 30 tuned by the action of short circuiting condenser 32. A transmission line 34 may then be coupled to the Lecher wire system as shown so 10 as to suitably load the same and feed into a radiating antenna 36.

Modulation is effected by virtue of variation in plate potential due to the action of transformer 10 in series with the plate 8. If desired, the secondary 15 of the transformer 10 may be inserted with similar effect in the lead 28 for the negatively maintained grid or grounded grid, or, in the lead 22 which maintains the grid 20 at a high positive potential.

20 It is to be noted that the perforations in the grids are arranged so as to be in line radially with respect to the filament. The alignment of the perforations is indicated by the dot and dash lines 40.

25 In the event that spiral grids are used, they should be so wound as to be of the same pitch and arranged so that when viewed in cross-section, the cross-sections will be in similar alignment as indicated in Figure 4. In the event that a rod-like 30 structure is used for grids, as shown in Figs. 5 and 6, the rods 26' and 20' of the respective grids in Fig. 5 and the rods 26'' and 20'' of the respective grids in Fig. 6 should be arranged so that they lie, in cross-section, upon the same radial line running through the cylindrical cathode or filament.

If desired, as already indicated, the inner grid (26, 26' and 26'') may be left floating, in which case electrons impinging thereon will give it the desired negative polarization.

40 Also, my improved tube may be used in a receiving system in which case antenna 36 would be a receiving antenna and the voltages and Lecher wire system 30 would be so adjusted that the tube would produce oscillations at the frequency of the 45 incoming waves. Hence, by virtue of an autodyne effect audio frequency energy may be derived from transformer 10 amplified by an audio frequency amplifier 6 and fed to a suitable translating device or loudspeaker 5. Here also, the transformer 10 50 may be placed in series with the other grid 26, or in series with the positively maintained grid 20. Also, for receiving, it is not necessary that the oscillator oscillate at the mean frequency of the received waves. The tube may be adjusted by 55 means of the voltages applied and the Lecher wire system to produce oscillations which will beat at a high frequency with the incoming waves. In that event, transformer 10 would be replaced by

a radio frequency transformer and rectangle 6 would indicate apparatus including a second oscillator and second detector as well as, if desired, audio frequency amplifiers for actuating loudspeaker 5. Here also the radio frequency 5 transformer 10 may be placed, if desired, in series with the inner grid 26 or outer grid 20.

What I claim is:

1. An electron discharge device comprising an electron emitting electrode, an electron receiving 10 electrode in cooperative relation with said first electrode, said electrodes being disposed one within the other, and insulating means interposed between only the aligned portions of said electrodes for preventing the flow of electrons in a rectilinear 15 path between said electrodes.

2. A Barkhausen oscillator comprising a cathode, an electrode in juxtaposition to said cathode, an electron receiving electrode intermediate said cathode and said first electrode, and insulating 20 means adjacent said electron receiving electrode for preventing the flow of electrons thereto in a rectilinear path from said cathode.

3. An electron discharge device comprising an electron emitting electrode, an electron receiving 25 electrode, a third electrode outside of said electron receiving electrode, and an insulating shield intermediate said electron emitting electrode and all portions of said electron receiving electrode in alignment with said electron emitting electrode. 30

4. An electron discharge device comprising a linear cathode, an electrode including a plurality of wires disposed parallel to one another and to said cathode and mounted in a cylindrical boundary about said cathode, and insulating shielding 35 means between aligned portions of said cathode and said wires.

5. An electron discharge device comprising a cathode, an anode and a pair of grid electrodes which have their grid wires in alignment in respect to the direction of electron flow, the grid electrode next adjacent the cathode being formed of dielectric material. 40

6. An electron discharge device comprising a cathode, a cylindrical outer electrode surrounding 45 the cathode, a pair of grid electrodes concentrically arranged about the cathode and interposed in the space between the outer electrode and the cathode, the grid electrode next adjacent the outer electrode being formed of conductive material, and the grid electrode next adjacent the cathode being formed of non-conductive material and disposed in the path of the electron flow from cathode to the conductive grid electrode whereby the electron flow between said electrodes in a rectilinear path is prevented. 50
